A. EPITAUX

ELECTROMAGNETIC DEVICE PRODUCING A CONSTANT MOVING FORCE

Filed Aug. 22, 1925

Inventor,
Albert Epitaux
By Henry Orth Jr. atty.

UNITED STATES PATENT OFFICE.

ALBERT EPITAUX, OF PARIS, FRANCE.

ELECTROMAGNETIC DEVICE PRODUCING A CONSTANT MOVING FORCE.

Application filed August 22, 1925, Serial No. 51,740, and in France September 2, 1924.

This invention relates to electro-magnets and has for its object an improved electro-magnet arrangement producing a constant moving force capable of finding its application in all the apparatus which need only a feeble moving force, but which force is continuous.

According to this invention I provide an electro-magnet comprising two pivoted or otherwise movable spring actuated armatures each provided with a contact piece adapted to close the existing current circuit when they are in contact, characterized in that the contact on one of the armatures which actuates the ratchet wheel is fixedly secured to said armature while the contact on the other armature is resiliently secured thereto, the latter armature having less inertia.

In operation, the motion of the armature which actuates a ratchet wheel, closes the existing electric circuit, the said circuit being held closed during the motion of the said first armature by the second armature of lesser inertia and therefore having a greater speed than the first, and so disposed as to make contact between the two contact pieces in the circuit as long as the motion of the first armature lasts, said first armature opening the circuit when it reaches the end of its movement, when the second armature is sharply pulled back in the inoperative position by a spring, the first armature closing the circuit again after having followed for a certain time the slow motion of the ratchet wheel, as it reaches its furthest position from the core of the electro-magnet.

Referring to the drawing left herewith:

The figure illustrates, as an example, one particular manner of carrying out the invention, and is a diagrammatic representation of an apparatus embodying the above described features.

A soft iron core 1 of a smaller section at one end than elsewhere carries a winding 2 producing under the action of the current the simultaneous attraction of the two armatures 3 and 4. The fixed yoke 5 completes the magnetic circuit. The armature 3 is extended by a lever 6 carrying a pawl 7. The spring 9 provides the motive force, transmitted by the pawl 7 to the ratchet wheel 8. When the armature 3 which slowly moves further from the core of the electro-magnet arrives at the end of its displacement, the contact piece 10 buts against the contact

spring 11 carried by the armature 4 and closes the electric circuit of the electro-magnet. The two armatures 3 and 4 are attracted, but as the armature 4 is endowed with a greater speed owing to its less inertia and its greater attraction, it maintains the contact spring 11 pressed against the contact piece 10 until the moment when the armature 3, arriving to its closest position to the core, abandons, by means of the contact piece 10, the contact spring 11; during this movement the pawl advances one tooth on the ratchet wheel 8.

Once the circuit is interrupted, the armature 4, actuated by the spring 12 is sharply pulled back to the non-operative position determined by the insulated stop-screw 13.

The armature 3 returns back but slowly, controlled in its motion by the rotation of the ratchet wheel 8. The cycle repeats again.

What I claim and desire to secure by Letters Patent of the United States is:

1. An electro-magnetic motor, comprising a soft iron core of reduced section at one end, a winding carried by said core, a fixed yoke completing the magnetic circuit, a first armature placed on the side of larger section of the core, a lever extending said armature on one side, a contact piece placed on the other side of the armature, a second armature opposite the smaller diameter of the core, a contact piece carried by said armature opposite the contact piece of the first armature, and means to draw the armatures back in their inactive position.

2. An electro-magnetic motor comprising a soft iron core of reduced section at one end, a winding carried by said core, a fixed yoke completing the magnetic circuit, a first armature placed on the side of larger section of the core, a lever extending said armature on one side, a pawl on said extension, a ratchet wheel engaging said pawl, a spring acting to draw back the armature, a contact piece on the other side of the armature, a second armature opposite the smaller section of the core, a contact spring carried by said armature opposite the contact of the first armature, an abutment screw upon the fixed yoke and a spring designed to draw back the second armature.

3. An electro-magnetic motor comprising: a soft iron core, a winding carried by said core, a first armature closing by means of a

contact piece the electric circuit of the electro-magnet, a second armature keeping the circuit closed during the movement of the first armature, said second armature possessing a greater attractive force, which produces a high pressure between the two electrodes of the contact, the pressure between

the two contacts lasting as long as the movement of the first armature, which opens the circuit when it reaches the end of its movement. 10

In testimony that I claim the foregoing as my invention, I have signed my name:

ALBERT EPITAUX.
